[57] CLAIM

I claim the ornamental design for a steering wheel cover, as shown and described.

DESCRIPTION

FIG. 1 is a top perspective view of a steering wheel cover showing my new design;

FIG. 2 is a bottom plan view thereof; and,

FIG. 3 is a side elevational view thereof.

The broken lines shown in FIGS. 1 and 2 are for illustrative purposes only and form no part of the claimed design.
